[57] CLAIM

The ornamental design for a dispensing cap, substantially as shown and described.

DESCRIPTION

FIG. 1 is a top plan view of a dispensing cap showing my new design.

FIG. 2 is a front elevational view thereof; the opposite side being a mirror image thereof;

FIG. 3 is a right end elevational view thereof;

FIG. 4 is a left end elevational view thereof;

FIG. 5 is a bottom plan view thereof;

FIG. 6 is a front elevational view thereof in open position;

FIG. 7 is a right end elevational view thereof;

FIG. 8 is a left end elevational view thereof; and

FIG. 9 is a partial sectional view taken along line 9—9 of FIG. 1.
